Primary Examiner — Daniel Bui*Assistant Examiner* — Andrew Kerr(74) *Attorney, Agent, or Firm* — Hauptman Ham, LLP(57) **CLAIM**

The ornamental design for a cup, as shown and described.

DESCRIPTION

FIG. 1 is a perspective view of a cup showing my new design;

FIG. 2 is a front elevational view thereof; the rear, left side and right side elevational views being identical to the front elevational view;

FIG. 3 is a top plan view thereof;

FIG. 4 is a bottom plan view thereof; and,

FIG. 5 is a reference cross-sectional view taken along line A-A' in FIG. 3, with two additional enlarged views showing a top edge portion and a bottom edge portion of the cup. The broken lines in the drawing views are included for the purpose of illustrating unclaimed portions only, and forms no part of the claimed design.
